(57) **CLAIM**

The ornamental design for a table, as shown and described.

DESCRIPTION

FIG. 1 is a perspective view of a table.

FIG. 2 is a front elevation view thereof. A rear elevation view, a left side elevation view and a right side elevation view are omitted because they are respectively identical to the front elevation view.

FIG. 3 is a top plan view thereof.

FIG. 4 is a bottom plan view thereof; and,

FIG. 5 is a cross sectional view thereof taken along Line 5-5 in FIG. 2.
